UNITED STATES PATENT OFFICE.

JAMES A. RANEY, OF CROSS CUT, PENNSYLVANIA.

SIEVE FOR MIDDLENS-PURIFIERS.

SPECIFICATION forming part of Letters Patent No. 237,597, dated February 8, 1881.

Application filed September 23, 1880. (No model.)

To all whom it may concern:

Be it known that I, JAMES A. RANEY, of Cross Cut, in the county of Lawrence and State of Pennsylvania, have invented a new and useful Improvement in Sieves for Middlens-Purifiers, of which the following is a specification.

Figure is a plan view of the improvement. Fig. 2 is a sectional end elevation taken 10 through the line xx , Fig. 1.

Similar letters of reference indicate corresponding parts.

The object of this invention is to furnish sieves for middlens-purifiers so constructed 15 that all parts of the sieve-cloths will be covered by the middlens, to prevent the air- blasts from passing through any uncovered portion of the sieve, and thus prevent the consequent waste of fine middlens.

20 In the accompanying drawings, A represents the sieve-frame, which is tapered upon both sides, or gradually decreased in width from the upper to the lower end.

To the upper end of the frame A is attached 25 the distributing-board B, which receives the middlens as they are introduced into the purifier, and from which they pass to the first sieve-cloth, C. The first sieve-cloth, C, is the finest and takes out the finest part of the middlens, or about half the volume. The coarser parts of the middlens, that cannot pass through 30 the cloth C, pass to the next cloth, D, and the next finest grade of the middlens is taken out, the coarser parts passing on to the next cloth, E, where they are again separated, and so on through the other cloths, F G, the coarse offal falling from the lower end of the sieve. With this construction each sieve or section or 35 number of cloth takes out about one-half the volume or quantity of the middlens that pass upon it, and each succeeding section or number of cloth is made about half the size of the preceding section, so that the entire surface of

the sieve-cloths will always be covered with middlens, to prevent the air-blast from passing through and carrying good middlens with it into the dust-room, thus causing a loss of fine middlens. The sieve-cloths C D E F G are secured along the central line of the sieve to a rib, H, the upper edge of which is a little 45 lower than the upper edge of the sieve-frame A, to prevent the middlens from working toward the sides of the sieve.

The sieve is provided with covering-plates I, to cover the outer parts of the sieve-cloths, 50 as indicated by dotted lines in Fig. 1, and shown in full lines in Fig. 2, which plates are adjustable, so that they can be arranged to regulate the proportional amount of exposed surface of the several numbers of sieve-cloths, 55 as the quality and quantity of the middlens to be separated may require. The covers I may be secured in place by pins, bolts, catches, or other suitable fastenings.

Having thus described my invention, I claim 60 as new and desire to secure by Letters Patent—

1. In a sieve for middlens-purifiers, the combination, with the tapered frame A and the tapered sieve-cloths C D E F G, of the 65 central rib, H, having its upper edge a little lower than the upper edge of the frame A, substantially as herein shown and described, whereby the middlens are kept from gathering at the sides of the sieve, as set forth. 70

2. In a sieve for middlens-purifiers, the combination, with the tapered frame A, and with the tapered sieve-cloths C D E F G, of the adjustable covers I, substantially as herein shown and described, whereby the amount 75 of exposed surface of the sieve-cloths can be regulated, as set forth.

JAMES ALEXANDER RANEY.
